UNITED STATES PATENT OFFICE

136,354

DESIGN FOR A BODY FOR AN AUTO SLED OR SIMILAR ARTICLE

Edward Porter, Akron, Ohio

Application June 24, 1943, Serial No. 110,510

Term of patent 14 years

To all whom it may concern:

Be it known that I, Edward Porter, a citizen of the United States, residing at Akron, in the county of Summit and the State of Ohio, have invented a new, original, and ornamental Design for a Body for an Auto Sled or Similar Article, of which the following is a specification, reference being had to the accompanying drawing, forming part thereof.

Figure 1 is a view in side elevation of a body for an auto sled or similar article embodying my new design;

I claim:

The ornamental design for a body for an auto sled or similar article, as shown.

EDWARD PORTER.
